UNITED STATES PATENT OFFICE

JOHN H. McLEAN, OF ANN ARBOR, MICHIGAN, ASSIGNOR TO ECONOMY BALER COMPANY, OF ANN ARBOR, MICHIGAN, A CORPORATION OF MICHIGAN

BALING PRESS

Application filed October 2, 1922. Serial No. 591,944.

The invention relates to baling presses and has for its prime object the provision of a baling press in which the platen is actuated by screw mechanism and is movable laterally of the baling chamber beyond its upper end so that material may be inserted into the chamber through its upper end. With this as well as other objects in view, the invention resides in the novel features of construction and combinations and arrangements of parts as more fully hereinafter set forth.

In the drawings:

Figure 1 is a perspective view of a baling press embodying my invention;

Figure 2 is an end elevation thereof;

Figure 3 is a plan view thereof;

Figure 4 is an enlarged vertical cross section through a portion thereof showing the manner of supporting the vertical screws.

1 is the base of the baling press, and 2 and 3 are respectively the frame and the baling chamber which are mounted upon the base. The frame has at opposite ends of the baling chamber the spaced vertical guide bars 4 connected by the cross bars 5 and secured at their lower ends to the saddles 6 resting upon the base. 7 is the platen movable vertically within the baling chamber 3 and actuated from the vertical screws 8 and 9 at the opposite ends of the baling chamber between the guide bars 4 and the cross bars 5 and the ends of the baling chamber. These screws are driven by suitable means such as the electric motor 10 which drives the drive shaft 11 extending longitudinally of the base 1 and provided with the bevel gears 12 meshing with the bevel gears 13 upon the lower ends of the screws.

For carrying the weight of the screws, the platen and the connections between the platen and screws, I have provided upon each screw the annular shoulder 14 which is supported upon the shoulder 15 surrounding the screw and forming part of the saddle 6. For resisting the upward thrust of the screw which is caused by the downward movement of the platen while compressing the material in the baling chamber, I have provided the annular shoulder 16 upon each screw and located below the shoulder 15 of the saddle.

There is preferably the anti-friction bearing 17 between the shoulders 16 and 15.

To permit of inserting the material into the baling chamber 3 through its open upper end, the platen is connected to the screws in such a manner that as it is raised out of and beyond the upper end of the baling chamber, it may be rocked laterally to clear the upper end, leaving the same open. Specifically, the platen 7 is secured to the supporting bar 18, which in turn is secured at its ends to the connecting rods 19 having hollow heads 20 at their upper ends for the passage of the screws therethrough. The lower ends of these connecting rods are pivotally connected to the nuts 21 threaded upon the screws and guided by the guide bars 4. The connecting rods are also preferably provided intermediate their ends with the vertically grooved transverse projections 22 for guiding engagement with the guide bars 4. To compel the platen to move over the upper end of the chamber after it has been raised beyond the same, there are the upwardly extending curved guide arms 23 upon the frame and engageable with the supporting bar 18 to force the platen laterally off dead center, after which it will move under the influence exerted by gravity as the nuts are raised until it assumes a position at one side of the chamber. Upon downward movement of the nuts, the connecting rods fulcrum intermediate their ends upon the frame as well as slide about their fulcrum points until the platen has moved into registration with the upper end of the baling chamber, after which further downward movement of the nuts lowers the platen.

Suitable anti-friction means such as the rollers 24 are preferably provided upon the frame for supporting the connecting rods intermediate their ends when tilted, these rollers facilitating the movement of the platen both to open position and to position in registration with the chamber.

What I claim as my invention is:

1. In a baling press, the combination with a base, of a chamber upon said base, a platen movable within said chamber and also transversely thereof, rotatable screws at opposite

ends of said chamber for raising and lowering said platen, longitudinally spaced shoulders upon said screws, and means secured to said base and located between said shoulders for limiting the longitudinal movement of and screws in opposite directions, said means including an anti-friction bearing.

2. In a baling press, the combination with a chamber having an open upper end, of a platen movable transversely of said chamber beyond said open end and also movable within said chamber, screws connected to said platen for actuating the same, and anti-friction means cooperating with said screws for supporting said platen when in a transverse position of adjustment.

3. In a baling press, the combination with a chamber having an open upper end, of a platen movable transversely of said chamber beyond said open end and also movable within said chamber, and means for actuating said platen comprising screws and connecting rods between said screws and platen, and anti-friction means engageable with said connecting rods when said platen is in a transverse position of adjustment.

In testimony whereof I affix my signature.
JOHN H. McLEAN.
